UNITED STATES PATENT OFFICE.

HARRY M. BIGELOW, OF MILWAUKEE, WISCONSIN.

SUGAR DISPENSING AND WEIGHING CONTAINER.

1,400,790.

Specification of Letters Patent. Patented Dec. 20, 1921.

Application filed March 4, 1920. Serial No. 363,201.

To all whom it may concern:

Be it known that I, HARRY M. BIGELOW, a citizen of the United States, and a resident of the city of Milwaukee, in the county of Milwaukee and State of Wisconsin, have invented a certain new and useful Improvement in Sugar Dispensing and Weighing Containers; and I hereby declare the following to be a full, clear, and exact description thereof, such as will enable persons skilled in the art to which the invention relates to make and use the same, reference being had to the accompanying drawing for a disclosure as to one construction in which the invention has been embodied.

The purpose of my invention is the production of a sanitary sugar container, adapted for use by dealers who dispense sugar to customers in small quantities. The container is provided with compartments for storing sugars of different grades, and one of such compartments is provided with a duct leading therefrom and over the mouth of a paper bag placed in the pan of a scale, supported by the container, so that sugar of the exact amount desired may be weighed out for the customer. The scale is set upon one of the faces of the container, and immediately below the scale the outer wall thereof is hollowed out to permit the free movement of the scale pan. The duct leading from the compartment described is provided with a closing gate, which may be opened to permit the sugar to flow from the container into the bag upon the scale pan, and which gate may be operated with precision as the pointer on the scale indicates that the amount of sugar has been drawn, and so stop the further movement of the sugar.

The compartment from which the duct leads is provided with an inclined bottom so arranged as to direct the sugar into the duct and permit the said compartment to automatically dispense all of the sugar contained therein. Arranged in the said compartment and above the inclined bottom thereof, is a comminuting screen, the purpose of which is to separate the fresh bulk of sugar when placed in the compartment, and reduce such bulk approximately to its granular consistency, so that the contents may flow freely through the duct when the gate is opened.

The lower part of the container is provided with a compartment for storing sugar of a

grade which is different from that which is stored in the upper compartment. Such lower compartment has an opening at an elevation above the bottom thereof, through which opening the bulk of the lower grade sugar may be inserted, and is provided also with a door near the bottom thereof which may be opened to permit the insertion of a scoop or measure by means of which the sugar may be manually withdrawn from the compartment and weighed and placed in the desired amount in the paper bag upon the pan of the scale.

It is my design to use the upper compartment of the container for the purpose of storing granulated sugar, which by reason of its nature may easily be dispensed through the duct, with no other effort than controlling the gate which normally closes the passage through the said duct. It is my purpose also to use the lower compartment for the storage of a grade of sugar for instance, brown sugar, not possessing the granular characteristics of the sugar stored in the upper compartment. As an adjunct to the arrangement described I have provided a third compartment of a lesser capacity and have located such third compartment at a point between the upper and lower compartments above described. Such third compartment is provided with a closing door, and is intended for the temporary storage of any overweights of granulated sugar which might accidentally be dispensed through the duct.

The features embodying the novelty in my invention will be pointed out in the appended claims.

In the accompanying drawings: Figure 1 is a plan view of my sugar dispensing and weighing container, a part of the cover thereof being broken out to show the interior arrangement.

Fig. 2 is a view showing the container in elevation and partly broken out to show the interior arrangement.

In constructing my improved container, I find it convenient to construct the same as a sheet metal drum, the circumference of which is formed with a plurality of flat faces, for the more convenient attachment of parts, although it is obvious that such drum may be cylindrical. In the drawing A indicates the drum, as described, the bottom B of which will rest upon the store counter or other suitable support. The top

C is provided with a circular opening *c* adapted to be closed by a tight fitting cover *c*¹ which latter is hinged as at *c*² to the top C. An inclined plate D placed within the 5 receptacle at a point intermediate its height, constitutes the bottom for the compartment E below the opening *c* in the top. Arranged upon one of the flat faces of the drum, and leading from the compartment E is a duct 10 *e*, the contracted outer end *e*¹ of which extends to a point at the center line of the flat face of the drum to which the said duct is attached. A measuring scale F is set within the face of the drum and slightly above 15 the outlet of the duct, from which scale depends a pan normally in position below the end *e*¹ of the duct. At its lower part the front face of the container is recessed as at G for the reception and movement of the 20 scale pan *f*, which latter is centered relatively to the end *e*¹ of the dispensing duct. It is designed that a square or flat bottomed paper bag shall be opened and placed in the pan of the scale, with the mouth of such bag in position to receive the sugar dispensed through the duct *e*. An arm *e*³ attached to the upper side of the duct has pivoted thereon a lever *e*⁴, to which is connected at *e*⁵ by means of a pin and slot connection 25 a gate *e*⁶ adapted to slide in an opening in the duct, so as to effectually close such duct and prevent the passage therethrough of any material other than at such times when the gate *e*⁶ is raised by lifting the lever *e*⁴. 30 35 The arrangement of the inclined plate D forming the bottom of the compartment is such that the granulated sugar placed in such compartment will be directed by the inclined surface of the said bottom member, so that the compartment may be entirely 40 emptied of its contents by being dispensed through the duct *e*, at such times as the latter may be opened for the purpose.

In the compartment E, a comminuting 45 screen *e*¹⁰ is supported upon a series of steps *e*¹¹ attached to the interior of the drum. The said screen is constituted of two parts, hinged at *e*¹², so that it may be folded and inserted through the opening *c* into its 50 proper position upon the supporting steps *e*¹¹, within the compartment. The screening portion is formed of a wire mesh fabric, of suitable gage. When the bulk of the sugar is dumped through the opening in the top 55 of the container, any lumps which may have been formed in such bulk will be broken by being forced against the screen, and thus the bulk of sugar will be reduced to its granular form, and in condition to be dispensed through the duct *e*.

The lower compartment of the container, comprising the space between the bottom B thereof and the inclined member D previously referred to, is provided with an opening in which is fitted a chute H, by means

of which sugar of a lower grade may be supplied to the said lower compartment. On one of the faces of the drum, adjacent to the scale pan a hinged door *h* leads to the lower compartment, which latter as stated 70 is intended to contain brown sugar or sugar of a lower grade than contained in the upper compartment. This lower compartment forms a very convenient adjunct for storing in proximity to the scale a quantity of 75 brown sugar so that such sugar may be readily accessible to meet the demands therefor, which are frequent but only occasional when compared to the demands for granulated sugar. By opening the door *h*, brown 80 sugar to the amount desired may be withdrawn from the lower compartment and placed in the bag previously set in the scale pan.

It is conceivable that in times of rush, an 85 amount of granulated sugar in excess of that called for, might be dispensed through the duct *e*. To meet such contingencies and afford a place for the immediate storage of such excess quantities of granulated sugar I 90 form a third compartment of relatively small dimensions, in one side of the container, and just below the upper compartment. This third compartment I is provided with a hinged door *i* by which the 95 opening thereto may be closed. A vertical wall *i*¹ indicated in dotted lines in Fig. 1, and bottom *i*² likewise indicated by dotted lines in Fig. 2, serve to partition off the space forming the third compartment I. 100 The overweights of granulated sugar accumulated in the third compartment I may be withdrawn therefrom and placed in the bag, preparatory to filling an order of sugar from the upper compartment. It will thus 105 be seen that no waste is involved.

My invention has been embodied in a practical form, such embodiment being illustrated in the accompanying drawing, and has been productive of satisfactory results. I 110 have produced a dispensing and containing apparatus which enables quantities of sugar to be stored in a most convenient manner, and have provided the device with a self-contained scale conveniently arranged for 115 effective use.

Having thus described my invention, what I claim and desire to secure by Letters Patent of the United States, is:

1. A dispensing and weighing container 120 provided with upper and lower compartments for storing sugars of different grades, a weighing scale attached to the outer side of the container, a pan depending from the scale, the container being recessed below the 125 scale to permit the free movement of the pan of the scale, the upper compartment being provided with an inclined plate forming the bottom thereof, a duct leading from the said plate and having its open end positioned to 130

discharge sugar from the upper compartment directly into a bag placed in the pan of the scale and a gate near the end of the duct.

5 2. A dispensing and weighing container provided with upper and lower compartments for storing sugars of different grades, a weighing scale attached to the outer side of the container, a pan depending from the 10 scale, the container being recessed below the scale to permit the free movement of the pan of the scale, the upper compartment having an inclined bottom and a duct adapt-

ed to direct the sugar flowing therefrom directly into a bag placed in the pan of the 15 scale a gate near the end of the duct, and an outlet opening from the lower compartment adjacent the pan of the scale.

In testimony whereof, I have signed my name at Milwaukee, this 28th day of Feb- 20 ruary, 1920.

H. M. BIGELOW.
